UNITED STATES PATENT OFFICE

LEWIS M. CLEMENT, OF MOUNTAIN LAKES, NEW JERSEY, ASSIGNOR TO F. A. D. ANDREA, INC., OF NEW YORK, N. Y., A CORPORATION OF NEW YORK

SOUND-REPRODUCING DEVICE

Application filed June 13, 1927. Serial No. 198,371.

My invention relates to sound reproducing devices generally known as loud speakers. My invention relates specifically to a device of this character having a sounding board 5 or sound radiator as distinguished from the sound box and horn type of such device.

My invention will be better understood by reading the following description in connection with the accompanying drawings, in 10 which

Fig. 1 is a vertical section of a device embodying my invention;

Fig. 2 is a section on line II-II of Fig. 1;

Fig. 3 is a sectional view of a part of the 15 motor unit;

Fig. 4 is a vertical section of a modification of the invention;

Fig. 5 is a vertical section of a further modification of the device;

20 Fig. 6 is a center section through a modified form; and

Fig. 7 is a front elevation of the form shown in Fig. 6.

Referring to the drawings, the device 25 consists of a standard or support 1 of any suitable design. Attached to the standard 1 are a number of horizontal supports 2 (in this case five). These supports may be attached to the standard by screws 3 or may 30 be made integral therewith. The motor 4 may be mounted on two parallel bars, one of which is shown at 5. The motor unit may be carried by side members 6 shown in section in Fig. 3. Any form of motor unit 35 may be used.

The sounding board or sound radiator is carried by the supports 2. The sounding board or sound radiator illustrated in Fig. 1 40 consists of a conical member 7, a frusto-conical member 8 and a baffle 9. The peripheries of the members 7, 8 and 9 are fastened together preferably by laying them against each other and placing a piece of braid 10 over them and stitching all of the parts in 45 place, as at 11. This construction forms a suitable union between the parts which is more durable than any of the forms of gluing or cementing. When the parts are in 50 position on the supports the baffle 9 lies in a plane at right angles to the longitudinal axis

of the members 7 and 8. The members 7, 8 and 9 are supported by the supports 2 by means of screws 12 which pass through the baffle 9 and enter the ends of the supports 2. The edge 13 of the frusto-conical member 8 55 is free and unsupported. If desired this edge may be provided with some form of damping means to prevent rattling. By supporting the sounding board or sound radiator through the baffle 9 in the manner shown and described it is supported at approximately its center of mass, which avoids any tendency on the part of the diaphragm to be distorted due to its own weight, and is free to respond to vibrations which are imparted to it by the motor unit through the member 14 which is attached to the apex of the member 7 by any suitable clutching or fastening mechanism 15. A conical stiffening member is snugly fitted into the apex 60 of the conical member, as will be explained in detail later. The driving member 14 is fastened to a pivoted transformer member 16 which is constructed so as to be as rigid as 65 possible in its plane of movement and which is pivoted around bearings 17 to a bracket 18 fastened onto the member 19 of the motor unit. The driving rod 14 is flattened at 14^a so as to allow it to bend in a plane passing through the longitudinal axis of the 70 transformer member 16 and the rod 14. The bearings 17 are between the ends of a hard pin 17^a and openings in the upturned ends of the member 18. The member 16 is connected with the armature 20 of the motor 75 unit through a member 21, having flattened portions 21^a to allow member 21 to bend readily. The armature is under the influence of the permanent horseshoe magnet 22, 80 and also the electromagnetic coil 23 which is actuated by the sound current impulses to be reproduced.

The baffle 9 is provided with an opening 24. The size of the opening 24 in the baffle 9 may be varied to secure the desired results 85 as to damping by controlling the air movement resulting from the actuation of the sounding board.

Referring to the modification shown in 90 Fig. 4, similar parts are marked with the 95 100

same numbers with the exponent a attached. In this modification the conical member 7^a is separate from the frusto-conical member 8^a thereby providing a space 25 between the peripheries of the members 7^a and 8^a . This arrangement provides a lighter sounding board or sound radiator. The frustum 8^a is rigidly attached to the standard 1^a and may be provided on its inner face with a lining 10 of felt 26 or other non-reflecting absorbent material to prevent reflection of sound. The cone 7^a is supported at approximately its center of mass by flexible members 27 through which screws 28 pass into the supports 2^a . This cone is also preferably provided around its periphery with a stiffening member 29 to dampen the periphery of the cone.

The periphery of the diaphragm 7^a , 7^b , Figs. 4 and 5, may be bound with braid for mechanical protection. The braid may be sewn as shown in Fig. 1. The braid may also act as a damping means for the periphery, but if the cone is sufficiently stiff it is not necessary for proper operation of the diaphragm. The diaphragm may be otherwise loaded to change its frequency characteristic in the desired manner, this loading or dampening ring may be applied to any portion of the diaphragm and it may be located either concentric with or eccentric to the center or apex (see Fig. 6). By proper choice of the diameter, width and mass of the ring and the proper location of it with respect to the apex, the response characteristic of the diaphragm may be modified as desired. The loading of the outer portion of the diaphragm in general affects the lower frequency and indirectly the higher frequency. The eccentric loading or dampening ring affects the wave which may be set up in the diaphragm and would otherwise cause out-of-phase radiation. The above may be applied to any type of diaphragm to improve or modify the response frequency characteristics. The cone is free to respond to the vibrations of the motor elements 14^a because of the flexibility of the members 27 . The effect of the frustum 8^a upon the action of the device may be varied by varying the opening 25 .

I have shown a further modification of my invention in Fig. 5, in which the same parts bear the same numbers with the exponent b attached. This modification is quite similar to that shown in Fig. 4, the chief difference being that the periphery of the frustum 8^b is curled over the periphery of the cone 7^b .

In Figs. 6 and 7 are shown two views of a further modification of my invention. In this form the sounding board is provided with eccentric damping means at 29^c . The eccentric damping means acts somewhat dif-

ferently from the concentric damping means 29 , shown in Fig. 4.

In this embodiment of the invention a reinforcement of paper, aluminum or other light material may be placed in the apex of the cone in order to render it strong and stiff. A light aluminum reinforcement may be cemented or otherwise fastened to the diaphragm and a light chuck 15^c riveted in place. The aluminum or other light reinforcement increases the efficiency of the diaphragm at the higher frequencies. The response characteristic of the diaphragm may be changed by the proper placing of annular stiffening rings or ribs 31 in the 80 stiffening member 32 . The annular stiffening ribs in the stiff conical reinforcing center piece allow this piece to be broken into a stiff central portion flexibly connected to the other outer portions by means of the annular ribs. The paper or other material used as the diaphragm provides damping means between these annular portions of the central stiffening cone. This construction increases the efficiency at the high frequencies by providing a diaphragm whose mass at high frequencies is lessened by partial isolation of the central portion of the diaphragm.

By the combination of the loading rings 29^c , either concentrically or eccentrically placed, of proper width and mass and by the placing of the light stiffening cone of proper size at the apex of the diaphragm the efficiency of the diaphragm may be increased at certain frequencies due to the fact that the impedance characteristic of the diaphragm can be changed as desired by the stiffening and loading means.

In general the smaller the diameter of the small central stiffening cone, the higher the frequency radiated from the diaphragm, and loading the outer edge of the diaphragm helps in the radiation of the low frequencies. Increasing the mass in general improves the efficiency at the lower frequencies.

The dissymmetrical loading of the diaphragm because of the abrupt change in constants of the diaphragm at the boundary of the loading causes reflection at those points, and because the distance from the center to these points is different, standing waves will not be set up to the extent they are with the circular diaphragm.

The diaphragm shown in Figs. 1, 4 and 5 may be also provided with stiffening means at the apex for the reasons just explained.

The efficiency of the flexible mountings on the front of the diaphragm may be increased by stiffening the material of the cone around the edges of the holes in the diaphragm by means of ribs, as shown in Fig. 6. These ribs may consist only of the material of the diaphragm, or if desired, metal such as aluminum may be attached to the diaphragm

and made to conform with the shape shown in Fig. 6.

In Figs. 6 and 7 a stiffening annular rib 30 is formed at the periphery of the dia-
5 phragm. If desired such a rib may be provided at the periphery of the diaphragm shown in Figs. 2, 4 and 5.

By the constructions above shown and de-
scribed faithful reproduction of sound is
10 produced at a higher efficiency than has been possible heretofore. The mechanical trans-
former from the armature 20 to the cone 7 is highly efficient because of the rigidity of
the member 16, the ease with which the same
15 may be moved around its pivot bearings 17 and the other elements of design shown and
described. The sounding board or sound
radiator is free to respond to the vibrations
20 of the motor unit because of its being sup-
ported approximately at its center of mass
which renders it free from any tendency of
distortion due to its own weight. Other
25 points of advantage will be apparent to
those skilled in the art.

25 I claim:

1. A sound reproducing device comprising
a flexibly supported sounding board, a mo-
tor for actuating said sounding board and a
30 flexible baffle for regulating the movement
of air produced by the actuation of said
sounding board and acting as the support
for the sounding board.

2. A sound reproducing device comprising
a conical sounding board element, a
35 motor for actuating said element from the
apex and a conical stiffening member
snugly fitted into the apex of the sounding
board element, said stiffening member hav-
ing stiffening rings.

40 3. A sound reproducing device comprising
a conical member and a frusto-conical
member, said members being fastened to-
gether at their peripheries and a baffle fas-
tened to said members and lying in a plane
45 at right angles to the longitudinal axis of
said members, means for supporting said de-
vice through said baffle and a motor for
actuating said device.

4. A sound reproducing device comprising
50 a conical member and a frusto-conical
member, said members being fastened to-
gether at their peripheries and a baffle fas-
tened to said members and lying in a plane
55 at right angles to the longitudinal axis of
said members, means for supporting said de-
vice through said baffle and a motor for
actuating said device, and an opening
through said baffle for controlling the move-
ment of the air agitated by said device.

60 LEWIS M. CLEMENT.
